UNITED STATES PATENT OFFICE

2,493,598

SELF-RETAINING ABDOMINAL RETRACTOR

Louis M. Rozek, Berlin, N. H.

Application August 6, 1948, Serial No. 42,872

2 Claims. (Cl. 128—20)

1

The present invention relates to self-retaining abdominal retractor and it consists in the combinations, constructions and arrangements of parts herein described and claimed.

It is an object of the present invention to provide an apparatus of the character set forth which is simple and inexpensive in its construction, easy to operate and efficient and effective in use.

Another object of the invention is the provision of a device of the character set forth which will eliminate the necessity for at least one attendant in surgical operations.

A further object of the invention is the provision of a device which will eliminate the uncertainty of the amount of tension applied to conventional retractors by eliminating the human element from such operation.

A further object of the invention is the provision of a device of the character set forth which readily lends itself to sterilization.

A further object of the invention is the provision of a retractor which may be set in position in the wound of a patient with one hand and which may also be removed by the use of one hand.

A still further object of the invention is the provision of an apparatus of the character set forth which may be rolled into a compact mass taking a minimum of space in sterilization apparatus.

Other and further objects of the invention will become apparent from a reading of the following specification taken in conjunction with the drawings, in which:

Figure 1 is a plan view of an embodiment of the invention in position upon the body of a patient.

Figure 2 is an elevational view of the device shown in Figure 1.

Figure 3 is an enlarged sectional view taken along line 3—3 of Figure 1.

Figures 4 and 5 are plan views illustrating certain elements of the invention.

Figures 6, 7 and 8 are perspective views illustrating certain elements of the invention, and

Figure 9 is an enlarged sectional view taken along line 9—9 of Figure 1.

Generally there is provided a self-retaining abdominal retractor consisting of a rectangular mat of canvas having a stitched in reinforcement comprising a steel rod along either side thereof. To one end of either side of the mat is attached a pair of table strap elements whereby the mat may be fastened over the body of a patient to

2

an operating table. At the other ends of the sides are affixed straps provided with buckles having hooks for engaging the undersides of the operating table. The mat is centrally provided with a relatively large circular opening having a wide reinforcing seam along its periphery. In spaced relation to the seam is placed a series of buckles for adjustably holding straps the inner ends of which are provided with retractors. The retractors are formed of sheet material and each comprise a surface portion extending toward the center of the wound, a retracting portion extending rearwardly therefrom at an angle of substantially 70° and peritoneal retaining portion likewise extending rearwardly but in parallel relation to the surface portion.

Referring more particularly to the drawings, there is shown therein a substantially rectangular shaped mat 10 preferably formed of canvas having a seam 11 along either side thereof in each of which seam is positioned a steel reinforcing rod 12.

At one end of either side of the mat 10 is affixed by stitching 13 one end of a table strap 14 which is provided with a conventional buckle 15. To the other ends of either side of the mat is affixed by stitching 16 a table strap 17 having a metallic tip 18 and provided with a buckle 19 the structure of which is illustrated more clearly in Figure 8.

The buckle 19 comprises a surface portion 20 having an integrally formed upwardly extending ear 21 at either side of its inner end and an integrally formed dependant hook 22 at its outer end. A strap retainer is provided and consists of a body 23 having a pair of integrally formed outwardly extending axles 24 revolubly mounted in the ears 21, an outwardly extending integrally formed curved handle 25 and, downwardly extending from its axial area, an integrally formed toothed strap-gripping plate 26.

The mat 10 is provided with a large circular opening 27 to the periphery of which is affixed by stitching 28 an overlapping preformed seam 29, to which is affixed at spaced intervals a series of retractor buckles 30 one of which is shown in greater detail in Figure 7.

The buckle 30 comprises a base plate 31 having openings 32 for stitching the same to the seam 29 and has integrally formed at its inner end a pair of upwardly extending ears 33. A strap retainer is provided for the buckle 30 and consists of a body portion 34 having a pair of integrally formed axles 35 journaled in the ears 33, an integrally formed outwardly extending curvular handle 36

and, at its inner end, an integrally formed, downwardly extending, toothed strap-gripping plate 37.

Adapted to be adjustably held by each of the buckles 30 is a retractor strap 38 having a metallic tip 39 at its outer end and a retractor 40 at its inner end. The retractor 40 is shown in detail in Figure 6 and comprises a surface portion 41 having a transversely extending slot 42 adjacent its outer end, a retracting portion 43 formed integrally therewith at its inner end and a peritoneal retaining portion 44 formed integrally with the retracting portion 43. The retracting portion 43 extends downwardly from the base portion and forms an angle of approximately 70° therewith and the peritoneal portion 44 extends in an outward direction and is parallel to the surface portion 41.

It will be understood that the terms "inwardly" and "outwardly" as used herein refer to the center of the device or the center of the circular opening 27.

In use, it will be apparent that the mat will be positioned on the body of a patient on an operating table 45 in such manner that the opening 27 encompasses the area to be operated upon. Thereupon the straps 14 are connected about the table 45 by the buckle 15. The buckles 19 are then connected with the sides of the table 45 by means of their hooks 22 and the straps 17 tightened beneath the body 23 and then gripped by the plates 26 by pressing downwardly upon the handles 25. The mat is prevented from "creeping" or wrinkling by means of the rods 12.

As a wound 46 is formed in the patient's body, the walls thereof may be held by placing the retractors in the wound at points selected by the surgeon whereupon the straps 38 are inserted into the buckles 30, the metal tips 39 thereof facilitating such procedure. When sufficient tension has been placed upon a retractor by the outward movement of a strap 38, the handle 36 of the buckle 30 will be depressed to thereby cause the teeth of the plate 37 to engage and hold the strap. Once so placed, the retractors 40 will remain in position and no unwarranted movement of the wound 46 will take place as is often the case where such retractors are held manually. The retractors may be quickly and easily removed by

merely lifting the handles 36 and disengaging the straps 38 from the buckles 30 and the device as a whole may be wrapped into a compact mass for sterilization. All of the metal parts mentioned herein are preferably formed of stainless steel or like rustproof material.

While but one form of the invention has been shown and described herein, it will be readily apparent to those skilled in the art that many minor modifications may be made without departing from the spirit of the invention or the scope of the appended claims.

What is claimed is:

1. A device of the character comprising a canvas mat having a circular opening, a wide preformed seam affixed adjacent the periphery of said opening, seams at either side of the mat, a metal rod in each of said last-mentioned seams, a series of buckles mounted on the preformed seam, retractors removably and adjustably mounted in said buckles, a table-engaging belt at one end of the mat and straps having hooked buckles at the other end of the mat.

2. A device of the character described comprising a canvas mat having a circular opening, a wide preformed seam affixed adjacent the periphery of said opening, seams at either side of the mat, a metal rod in each of said last mentioned seams, a series of buckles mounted on the preformed seam, retractors removably and adjustably mounted in said buckles, a table-engaging belt at one end of the mat and straps having hooked buckles at the other end of the mat, said retractors each comprising a surface portion, a downwardly directed retracting portion at an angle of 70° to said surface portion, a peritoneal engaging portion parallel to said surface portion and a metal-tipped strap affixed to the surface portion.

LOUIS M. ROZEK.
